UNITED STATES PATENT OFFICE.

SALLY S. SPOFFORD, OF PEABODY, MASSACHUSETTS.

GARMENT-FASTENER.

SPECIFICATION forming part of Letters Patent No. 717,940, dated January 6, 1903.

Application filed April 24, 1902. Serial No. 104,565. (No model.)

To all whom it may concern:

Be it known that I, SALLY S. SPOFFORD, a citizen of the United States, and a resident of Peabody, in the county of Essex and Commonwealth of Massachusetts, have invented 5 certain new and useful Improvements in Garment-Fasteners, of which the following is a specification.

This invention relates to garment-fasteners; and its object is to provide a device that when attached to a corset will keep the belt and garments in place at the waist and will also reinforce the corset-steel.

In the drawings, Figure 1 represents the blank from which the fastener is formed. Fig. 2 is an end view of the fastener. Fig. 3 is a side view. Fig. 4 is a front elevation, and Fig. 5 shows the fastener in place upon a corset.

20 The fastener is represented as formed from a blank which may be stamped from a single sheet of metal. The arms a a' are bent on the lines indicated by the dotted lines in Fig. 1 until they lie opposite the arms a^2 and a^3 , 25 respectively, and the part a^4 is bent on the dotted lines into the form of a downwardly-directed hook, as shown in Figs. 2 and 3. The arms a , a' , a^2 , and a^3 are each perforated, as represented in the drawings, so that the 30 perforations in the arms a and a' come opposite to those in the arms a^2 and a^3 , respectively, when the former arms are bent into position above those last mentioned, respectively.

35 When the fastener is slipped upon the edge of the corset, as shown in Fig. 5, the corset-steel B at the edge of the corset is clasped by the pairs of arms a a^2 and a' a^3 and the fastener is held firmly thereby. The fastener 40 may also be secured to the corset by sewing it thereto through the perforations x or around the ends of the arms. When in position upon the corset, the main portion a^0 of the fastener lies against the corset-steel B 45 on the inside of the corset, as shown by dotted lines in Fig. 5. The arms a^2 a^3 are also on the inside of the corset, and only the arms a a' and the hook a^4 are exposed to view. The hook a^4 is offset sidewise with reference to 50 the shank A in order to bring the hook in the center of the front of the figure, while the fastener-arms fit on the edge of the corset-steel. When the fastener is in place upon

the corset, the hook a^4 is in position to keep in place the belt, waist, and skirts of the 55 wearer, so that pins and other fastening devices may be dispensed with. The fastener is rigidly attached to the corset and cannot move sidewise and cause lateral displacement of the garments held by it. 60

An important feature of the device is found in the fact that the hook a^4 lies at the center of the figure, which insures that the garments with which it engages will hang straight. The portion a^0 of the fastener, lying, as it does, 65 against and along the steel B , affords a reinforcement for said steel and at the point where it is most needed, for the fastener when it is in proper position for the hook to engage the garment that it is to keep in place is brought 70 opposite to that part of the steel that is subjected to the greatest strain. This reinforcement of the corset-steel at the waist is an important feature of my invention. The device, however, may be placed at any position along 75 the front corset-steel as the wearer may desire and as indicated in Fig. 5.

What I claim is—

1. A blank for a garment-fastener stamped from a single piece of metal, consisting of a 80 shank adapted to reinforce the corset-steel upon its inner side; oppositely-placed arms on either side of said shank, and a piece upon one of said parts adapted to be formed into a downwardly-directed hook; substantially as 85 described.

2. A blank for a garment-fastener stamped from a single piece of metal, consisting of the shank a^0 , the pairs of arms a , a^2 and a' , a^3 for securing the fastener to the corset; and the 90 piece a^4 on the arm a , adapted to be formed into a downwardly-directed hook; substantially as described.

3. A garment-fastener formed from a blank stamped from a single piece of metal and comprising the shank a^0 adapted to lie against the corset-steel on the inside of the corset, the pairs of arms a , a^2 , and a' , a^3 , for securing the fastener to the corset, and the sidewise-offset and downwardly-directed hook a^4 on 100 one of said arms, substantially as described. 95
